UNITED STATES PATENT OFFICE

127,404

DESIGN FOR A FIREMAN'S HELMET OR SIMILAR ARTICLE

Edward Cairns, Montclair, N. J.

Application July 25, 1940, Serial No. 93,912

Term of patent 14 years

To all whom it may concern:

Be it known that I, Edward Cairns, a citizen of the United States and resident of Montclair, in the county of Essex and State of New Jersey, have invented a new, original, and ornamental Design for a Fireman's Helmet or Similar Article, of which the following is a specification, reference being had to accompanying drawings, forming a part thereof in which—

Fig. 2 is a side elevational view of the fireman's helmet shown in Fig. 1;

Fig. 3 is a front elevation of said fireman's helmet; and

Fig. 4 is a rear elevation of the fireman's helmet.

I claim:

The ornamental design for a fireman's helmet or similar article, as shown.

EDWARD CAIRNS.
